UNITED STATES PATENT OFFICE.

WILLIAM F. DURYEA, OF NEW YORK, N. Y.

DESIGN FOR A WATCH-CHAIN BAR.

SPECIFICATION forming part of Design No. 19,759, dated April 15, 1890.

Application filed March 18, 1890. Serial No. 344,424. Term of patent 3½ years.

To all whom it may concern:

Be it known that I, WILLIAM F. DURYEA, of the city, county, and State of New York, have invented and produced a new and original Design for a Watch-Chain Bar, of which the following is a full, clear, and exact specification.

The figure represents a bar or guard embodying my design.

The leading feature of my design is a bar-like figure B, having a central bend at c and two opposite bends at b, the outer ends b' thereof aligning. From the outward extremi-

ties of the bar-like figure extend laterally the curved lines B', the extremities of which are united by the oval figures C. At the center of the bar are the bead-like bands c', below which is the link-like figure a.

I claim—

The design for a watch-chain bar herein shown and described.

WILLIAM F. DURYEA.
